NAPKIN HOLDER

John A. Ericson, Youngstown, Ohio

Application February 20, 1956, Serial No. 40,220

Term of patent 14 years

(Cl. D44—24)

I claim:

The ornamental design for a napkin holder, as shown.
